UNITED STATES PATENT OFFICE.

ALEXANDER C. THOMAS, OF HOUSTON, MISSISSIPPI.

WOODWORKING-TOOL.

1,051,526.

Specification of Letters Patent. Patented Jan. 28, 1913.

Application filed July 17, 1911. Serial No. 638,946.

To all whom it may concern:

Be it known that I, ALEXANDER C. THOMAS, a citizen of the United States, residing at Houston, in the county of Chickasaw and State of Mississippi, have invented a new and useful Woodworking-Tool, of which the following is a specification.

This invention relates to woodworking tools and more particularly to a tool especially designed for producing rounded surfaces upon wooden strips and the like.

One of the objects of the invention is to provide a simple, durable and inexpensive tool of this character which can be easily manipulated and which is especially desirable for use in making wheel spokes by hand.

A further object is to provide a woodworking tool which can be quickly sharpened throughout the length of its cutting edge.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings:—Figure 1 is a perspective view of the tool. Fig. 2 is a section on line A—B Fig. 1.

Referring to the figures by characters of reference 1 designates a semi-elliptical blade the terminals of which are reduced to form stems 2, these stems being preferably bent or folded to form elongated loops 3 constituting efficient handles. It is to be understood, however, that if preferred wooden handles or any other types of han-

dles may be secured to the stems 2. The upper and lower faces of the blade 1 are parallel and the lower portion of the lower blade is beveled to form the inner or cutting edge of the blade and both of said faces are inclined downwardly relative to the plane occupied by the outer edge of the blade. This will be clearly apparent by referring to Fig. 2.

As the blade has a cutting edge curved from end to end and lying in a plane parallel to that in which the stems or handles 2 are located, it will be apparent that when the tool is placed upon stock to be shaped and is pulled toward the operator, the curved edge will cut the stock so as to produce a rounded surface thereon.

When it is desired to sharpen the tool, the cutting edge 4 thereof is placed flat upon a sharpening stone and the tool is then reciprocated upon the stone and all portions of the cutting edge will thus be simultaneously acted upon. It will thus be apparent that cutting edge 4 is always flush with the upper surface of the blade 1.

What is claimed is:—

A woodworking tool formed in a single piece of metal and including an arcuate blade, and handles extending from the ends of the blade, the upper and lower faces of the blade being inclined downwardly and inwardly from the convexed edge of the blade and merging to form an arcuate cutting edge extending continuously from one end to the other of the blade and having all points thereof located in a plane below and parallel with the plane occupied by the handles.

In testimony that I claim the foregoing as my own, I have hereto affixed my signature in the presence of two witnesses.

ALEXANDER C. THOMAS.
